UNITED STATES PATENT OFFICE.

HARRY J. HICK, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

FILING APPLIANCE.

1,190,895.

Specification of Letters Patent.

Patented July 11, 1916.

Application filed August 6, 1914. Serial No. 855,441.

To all whom it may concern:

Be it known that I, HARRY J. HICK, a citizen of the United States, residing at Alliance, in the county of Stark and State of Ohio, have invented certain new and useful Improvements in Filing Appliances, of which the following is a specification.

The invention relates to a filing appliance for sales bills and other similar papers, in which a series of bill holders are operatively mounted in a fire-proof case comprising a rectangular base section, and a similar cover section adapted to be swung and shifted upon the base section to incase the bill holders when closed, and to form a back for the same when open.

In a former application, filed July 25, 1914, Serial No. 853,062, a filing appliance of this type or character has been illustrated, described and claimed, in which a portion or division of the series of hinged holders have their hinged ends pending from a pivotal connection with the rear rim of the cover section, with means for supporting and guiding the free end of the holders upward and forward from within the base section over the forward rim thereof, and extensible frames within each side of the case having counterbalancing springs therein for the cover section of the case and elevating and sustaining springs therein for the pending hinged ends of the holders.

The object of the present invention is to provide improved operative connections between the elevating and sustaining springs and the hinged end of the lower holder. This object is attained by pivoting a swinging link to the head of the elevating and sustaining springs, by providing a longitudinally slotted lifting lever with its rear end pivoted in the rear end of the case and its forward end pivoted to the lower end of the swinging link, and by providing lateral pins on the hinged end of the lower holder or its supporting frame operating in the longitudinal slot of the lifting lever for elevating and sustaining the hinged end of the lower holder.

A preferred embodiment of the improvement, thus briefly set forth, is illustrated in the accompanying drawings, forming part hereof, in which—

Figure 1 is a side elevation of the case, showing the cover section closed downward upon the base section thereof; Fig. 2, a simi-

lar view with the side of the case broken away to show the bill holders and operative parts inclosed therein; Fig. 3, a side elevation section of the case, showing the cover section swung upward upon the rear end of the base section and the bill holders carried upward and forward into reclined operative position; Fig. 4, a similar section showing the upper division of bill holders rotated into upright position, the lower division of bill holders remaining in reclined position and parts of the spring frame being broken away to show structural details; and Fig. 5, a similar section showing the lower division of bill holders swung into upright position.

Similar numerals refer to similar parts throughout the drawings.

The case is composed of the substantially rectangular bottom or base section 1 and the top or cover section 2, which are operatively connected together by means of guiding hinge brackets 3, one being located on each side of the rear end portion of the base section; by means of which the cover section can be swung and shifted upon the base section to aline either the top or rear end of the cover section with the rear end of the base section.

The series of bill holders 4 and 4' are hinged together at their lower rear ends, and the pivots 5 between two adjacent intermediate holders 4^a and 4^b' are mounted in the bearings 6 secured to the rear rim of the cover section; so that the holders above these bearings may be referred to as the upper division of the series, and the holders below these bearings may be referred to as the lower division of the series.

The lower forward bill holder 4^a' of the series is pivoted at 7 to the rear end of the frame 8, which preferably contains an index, not shown, for the bill holders; and inclined tracks 9 are provided in the forward end of the base section of the case, on which tracks the forward end of the frame 8 may slide downward and rearward into the base section when its rear end is carried downward and rearward by its pendent connection with the rear rim of the cover section, when the same is closed downward upon the base section as shown in Fig. 2.

The counterbalance frame is composed of the bearing head 10 on its lower end, the outer and inner guide rods 11 and 12 secured to the bearing head at the lower ends,

the main sliding head 13 having apertures 14 therein for each of the guiding rods 11 and 12, and the minor sliding head 15 having apertures 16 therein for the inner guide rods 12.

The outer and inner coiled compression springs 17 and 18 are located around the outer and inner guide rods 11 and 12, the outer spring extending between the bearing head 10 and the main sliding head 13, and the inner springs extending between the bearing head 10 and the minor sliding head 15.

The lower end of the bearing head is 15 pivoted on the post 19 secured to the side wall in the forward portion of the base section of the case, and preferably near the bottom thereof; and the main sliding head is pivoted on the post 20 secured to the side 20 wall in the rear of the middle of the cover section of the case and preferably below the median line thereof.

The swinging link 21 is pivoted at its upper end to the inner side of the minor sliding head 15 and at its lower end to the forward end of the lifting lever 22, the rear end of which is pivoted at 23 in the rear end of the base section of the case.

The lifting lever 22 is provided with a 30 longitudinal slot 24 from one end to the other, and the lateral pins 25 are provided on the hinged ends of the frame 8, which pins extend into and are adapted to slide along the longitudinal slot 24 in the operation 35 of the appliance.

The parts and the strength of the springs are so proportioned and arranged that when the cover section is swung and shifted into upright position upon the rear end of the 40 base section of the case with the bill holders carried forward into reclined position, as shown in Fig. 3, the main head 13 will slide upward to the extreme upper ends of the guide rods 11 and 12, and the engagement 45 of the lateral pins 25 in the slot of the lifting lever 22 draws the pendent link 21 and the minor sliding head 15 downward on the guide rods 12 a substantial distance below the main head 13 so as to compress the inner springs 18, as shown in the same figure.

In this relation of the parts it is evident that the bill holders 4, 4^a and 4^b, comprising the upper division of the series, may be rotated upon their hinged ends into upright position, either singly or collectively; in which upright position the upper-rear holder of this division is sustained and guided by the abutment rollers 26 provided on the sides of the cover section, and the forward 55 holder 4^a thereof is supported by the pivotal bearings 6 on the rear rim of the cover section, all as shown in Fig. 5; so that the rotated holders of this division will be maintained in upright position by the action of 60 gravity in the manner well known in this

art. Furthermore, when one or more of the bill holders 4', 4^a' and 4^b', comprising the lower division of the series, are rotated on their hinged ends into upright position, as shown for all these holders in Fig. 5, the energy of the inner compression springs 12 acting through the links 21 will lift the levers 22 upward, thereby elevating and sustaining the hinged ends of the frame 8 and the holders thereon; so that all the holders 70 in the lower division of the series which have been rotated into upright position, will be maintained in such position by the sliding and bearing of the lateral pins 25 in the forward portion of the longitudinal slot 24 75 in the lifting lever 22.

For closing the case, it is preferred to rotate all the bill holders of the series forward upon their hinged ends into reclined positions, superposed upon the frame 8, as shown 80 in Fig. 3; whereupon a forward swinging and rearward shifting of the cover section to close it upon the base section will carry the frame 8 and superposed holders thereon bodily downward and rearward within the 85 two sections of the case, as shown in Fig. 2; during which movement the forward end of the frame 8 slides downward upon the 90 guide rods far enough to impinge the minor slide 100 head 15, whereupon the energy of the outer compression springs 17 will be supplemented by the energy of the inner compression springs 18; so that all the compression springs will serve to counterbalance the 95 weight of the cover section until the main head 13 slides downward upon the guide rods 105 far enough to impinge the minor slide 100 head 15, whereupon the energy of the outer compression springs 17 will be supplemented by the energy of the inner compression springs 18; so that all the compression springs will serve to counterbalance the 105 weight of the cover section during the final portion of this downward movement toward and upon the base section of the case; and reversely, all the compression springs will serve to assist in elevating the cover section 110 during the first portion of its movement into upright position.

It will be understood that as the frame 8 and the superposed holders are carried downward and rearward within the case, 115 the lateral pins 25 on the rear end of the frame will slide rearward along the longitudinal slot 24 in the lifting lever 22 to the rear end thereof, as shown in Fig. 2; during which movement the lifting lever rocks 120 downward upon its rear end pivot to or near the bottom of the case; and that if necessary, the pivotal bearing in the upper end of the pendent link 21 may be slotted to accommodate the parts in this relation. It will also be understood that for the purpose of the present invention the frame 8 may be considered merely as the lower holder of the series, or that the lateral pins 125 may be located on the holder next above the 130

frame instead of being connected therewith by means of the frame, without making any material change in the operation of the parts. And finally, it is preferred to bend 5 or deflect the lifting lever and its longitudinal slot upward at or near the place intermediate its ends where the frame pins bear when the holders of the lower division are in reclined operative position, as shown in 10 Fig. 4; so the forward portion of the lever is positioned to properly perform its lifting functions.

I claim:

1. A filing case including similar base 15 and cover sections with hinge connections for swinging the cover section upon the base section, a plurality of hinged holders mounted in the case having their hinged ends depending from a pivotal connection 20 with the rear end of the cover section, a lifting lever having its rear end pivoted in the rear end of the base section, spring means for elevating the forward end of the lifting lever, and means connected with the hinged 25 end of the lower holder having sliding and bearing engagement with the lifting lever.

2. A filing case including similar base and cover sections with hinge connections for swinging the cover section upon the base 30 section, a plurality of hinged holders mounted in the case having their hinged ends depending from a pivotal connection with the rear end of the cover section; a spring-sustained swinging link, a lifting 35 lever having its rear end pivoted to the base section and its forward end pivoted to the swinging link, and means connected with the hinged end of the lower holder having bearing and sliding engagement with the 40 lifting lever.

3. A filing case including similar base and cover sections with hinge connections for swinging the cover section upon the base section, a plurality of hinged holders 45 mounted in the case having their hinged ends depending from a pivotal connection with the rear end of the cover section; counterbalance means for the cover section including a bearing head pivoted to the base

section having a plurality of guide rods 50 thereon, and a main head pivoted to the cover section having sliding engagement with the rods; and lifting means for the holders including a minor head in the path of the main head having sliding engagement 55 with certain rods, a swinging link depending from the minor head, a lever containing a longitudinal slot having its rear end pivoted to the base section and its forward end pivoted to the swinging link, and lateral 60 pins connected with the hinged end of the lower holder for bearing and sliding in the slot of the lever; there being compression springs on the guide rods between the bearing head and the respective sliding heads. 65

4. A filing case including similar base and cover sections with hinge connections for swinging the cover section upon the base section, a plurality of hinged holders mounted in the case having their hinged 70 ends depending from a pivotal connection with the rear end of the cover section; means for supporting and guiding the forward ends of the holders upward and forward over the forward rim of the base section; counterbalance means for the cover section including a bearing head pivoted to the base section having a plurality of guide rods thereon, and a main head pivoted to the cover section having sliding engagement 80 with the rods; and lifting means for the hinged ends of the holders including a minor head in the path of the main head having sliding engagement with certain rods, a swinging link depending from the 85 minor head, a lever containing a longitudinal slot having its rear end pivoted to the base section and its forward end pivoted to the swinging link, and lateral pins connected with the hinged end of the lower 90 holder for bearing and sliding in the slot of the lever; there being compression springs on the guide rods between the bearing head and the respective sliding heads.
